● *To all whom it may concern:*

Be it known that I, CARL R. HELLMAN, a citizen of the United States of America, residing at 150 West 82d Street, New York, New York, have invented a new, original, and ornamental Design for a Textile Fabric or Similar Article, of which the following is a specification, reference being had to the accompanying drawing, forming a part thereof.

The figure is a plan view of a textile fabric showing one fourth of the unit of my new design. The full lines of the drawing show one eighth of the design in detail, the other

The other three fourths of the unit are arranged about the common center, indicated by the intersecting dot and dash lines, in the same relationship as indicated in the illustrated one fourth.

I claim:

The ornamental design for a textile fabric or similar article as shown and described.

In testimony whereof I have signed this specification.
